UNDERFRAME STRESS RELIEF MEANS

James C. Travilla, Ladue, and John R. Vogel, Northwoods, Mo., assignors to General Steel Industries Inc., Granite City, Ill., a corporation of Delaware
Filed Aug. 5, 1965, Ser. No. 477,564
4 Claims. (Cl. 105—420)

ABSTRACT OF THE DISCLOSURE

Underframe structure, particularly for railroad cars having longitudinally slidable draft sills, in which the bolster side walls are eliminated across the center sill to accommodate the slidable draft sill. To prevent stress concentrations in the bolster bottom wall across the center sill, at the intersection of the bottom wall horizontal portion with the depending center plate boss, arcuate cross section grooves are provided in the bottom wall along the sides of the intersection to permit a greater radius of intersection than would otherwise be possible without reducing the clear height of the center plate boss.

The invention relates to railway rolling stock and consists particularly in an improved underframe structure for cars having floating draft sills.

In cars of this type, to permit the positioning and free longitudinal movement of the draft sill within the underframe center sill, it is necessary that the interior of the latter be unobstructed throughout the length of the car. This requirement creates special problems at the center plate locations, where the body bolsters intersect the center sill. The body bolster is essentially a transverse beam loaded at its ends by the car side walls and supported at its midpoint by the car truck. In conventional cars of the fixed center sill type, one or more vertical webs extend transversely through the center sill at the bolster location to provide resistance to the high vertical bending moments in this region and to reinforce the bottom web of the bolster, which forms its compression member under vertical loading.

The absence of any vertical webs across the center sill is complicated by the further fact that the center plate, formed by a circular boss in the bottom wall of the bolster, normally intersects the horizontal portion of the bottom wall substantially at right angles, the latter being required to avoid interference with the upstanding circular rim of the truck center plate. In view of the fact that the bottom wall of the bolster must function as the compression member of the bolster, serious stress concentrations are encountered at the right angle intersections at the sides of the center plate, becoming less critical fore and aft of the center plate. Such stress concentrations tend to cause failures in this critical area.

It is accordingly an object of the invention to provide an underframe end structure, for cars with floating draft sills, with a strengthened bottom wall in the center plate region. A further object is to provide such a construction in which the stress concentrations at both sides of the center plate are substantially reduced.

The foregoing and additional more detailed objects and advantages will be achieved by the construction described hereinafter and illustrated in the accompanying drawings, in which:

FIG. 1 is a longitudinal vertical sectional view, along longitudinal center line 1—1 of FIG. 3 of an underframe end casting embodying the invention, in its normal service position.

FIG. 2 is a transverse vertical sectional view along the bolster center line 2—2 of FIG. 3.

2

FIG. 3 is a bottom view of the casting illustrated in FIGS. 1 and 2 taken from line 3—3 of FIG. 2.

FIG. 4 is an enlarged fragmentary bottom view showing the center plate region of the casting.

FIGS. 5—8 are enlarged fragmentary vertical sectional views of the center plate portion of the bottom wall in normal service position corresponding to FIGS. 1 and 2, taken along lines 5—5, 6—6, 7—7 and 8—8, respectively, of FIG. 4.

FIGS. 9 and 10 are enlarged fragmentary vertical sectional views, corresponding to FIG. 5, of modified forms of the invention.

The underframe includes an end structure, preferably of cast metal and cruciform in plan, comprising an outer relatively long center sill portion 1, an inner relatively short center sill portion 3 arranged for attachment to an end of an intermediate center sill (not shown), and identical body bolster arms 5, 5 intersecting center sill 1, 3 between its outer and inner portions 1 and 3.

The center sill 1, 3 is an inverted outwardly flanged channel comprising a flat top wall 7, and spaced, longitudinally extending vertical side walls 9 outwardly horizontally flanged along their lower margins as at 11.

The body bolster arms 5, 5 are of box section, each comprising a substantially horizontal top wall 13 merging with center sill top wall 7, vertical side walls 15 spaced apart lengthwise of the structure and arcuately merging at their inner ends with the vertical side walls 9, 9 of center sill 1, 3, and a bottom wall 17, into which center sill flanges 11 merge. Intermediate their ends, each of the bolster arms is formed with a downwardly facing side bearing 14, and the bolster arms also include full height internal central ribs 16 merging at their inner ends with center sill side walls 9 and extending outwardly therefrom well past side bearings 14.

To additionally tie the side bearings into the bolster side walls 15, additional ribs 18 extend the full width of the bolster up from the bottom wall over the side bearings. Additional strength is imparted to the connection between the bolster arms and center sill by pairs of short ribs 20 extending outwardly from center sill side walls 9 and disposed on both sides of bolster center web 16 and in spaced relation thereto.

The intermediate portion 19 of bottom wall 17 extends across the center sill and is formed with a depending hollow cylindrical boss or body center plate having an upright cylindrical side wall 21 and a flat bottom wall 23.

Center plate 21, 23 is arranged for mating pivotal engagement, as a male part, with a female part formed by an upstanding rim R on the top of a truck bolster. Rims R are of standard height, to permit interchangeability from car to car, and the height of the bottom surface of bottom wall central portion 19 is fixed by other factors which severely limit the height of upright cylindrical wall 21 to a dimension just sufficient to provide clearance between the top of rim R and the bottom of bottom wall 19.

To reduce the stress concentration at the sides of center plate 21, 23, which would occur if the center plate upright wall 21 intersected bottom wall 19 at a right angle or on a negligible radius at the sides, a large radius intersection is provided at the sides by forming a groove 25 of generally crescent shape in plan partly in the bottom wall 19 and partly in the upright cylindrical wall 21 on both sides of the center plate, groove 25 being arcuate in vertical cross section of sufficient radius to provide the desired reduction in stress concentration. This maximum radius, shown in FIG. 5, is provided through an arc extending approximately 20° on both sides of the transverse center line as best seen in FIG. 4, the radius and depth of the recess gradually diminishing through the next 25° until

70 the recess terminates and the minimum radius is reached at about 45° on each side of the transverse center line,

the latter obtaining along the generally transverse margins of the center plate between the grooves at each side.

As seen in FIGS. 5-8, this arrangement provides a large radius intersection between the horizontal bottom wall portion 19 and upright cylindrical wall 21 at both sides of the center plate, and by being recessed into the two walls it does not interfere with the clearance required for the truck center plate rim R.

Additional strength is provided across the center sill by the provision on the bottom of wall 19 of spaced pairs of continuous transverse ribs adjacent the forward and rear margins of bottom wall 19 and by pairs of discontinuous ribs 29 disposed slightly inwardly, longitudinally of the sill of center plate cylindrical wall 21 and extending transversely inwardly from their outer ends, which are substantially aligned with the outer ends of ribs 27, and then curved in spaced relation with the margins of center plate wall 21 toward the adjacent rib 27 transversely outwardly from the margin of recesses 25, after which they merge into bottom wall 19 a short distance from ribs 27. Further strength is supplied across the center plate by a transverse diametral rib 31 wholly within the center plate depression in wall 19, while additional strength is supplied to the sill across the center plate by a longitudinally extending narrow box section member comprising bolster bottom wall 19, center plate bottom wall 23, spaced longitudinally extending vertical side walls 33 and top wall 35.

In the embodiment illustrated in FIG. 9, stress relief is accomplished by a large radius arcuate groove 37, wholly disposed in bolster bottom wall 19' and tangent to the outer side surfaces of the cylindrical wall 21'.

In the embodiment illustrated in FIG. 10, the arcuate groove 39 is wholly disposed in the cylindrical wall 21" and is tangent to the bottom surface of bottom wall 19".

As in the first disclosed embodiment of the invention, grooves 37 and 39 are formed at the sides only of the center plate, i.e., in the quadrants bisected by the transverse diameter of the center plate and are of the maximum depth and radius throughout the same arc as in the first embodiment, i.e., approximately 20° on both sides of the transverse diameter gradually diminishing therefrom in depth and radius to a negligible radius throughout the quadrants bisected by the longitudinal diameter of the center plate.

The details of the structure may be modified substantially without departing from the spirit of the invention, and the exclusive use of such modifications as come within the scope of the appended claims is contemplated.

What is claimed is:

1. Underframe structure for a railroad car comprising a transverse beam underlyingly supported at its center and vertically loaded at its ends, said beam having spaced top and bottom walls forming respectively its tension and compression members, the central portion of said bottom wall comprising a depending vertically disposed cylindrical boss and a horizontal wall portion surrounding said boss and perpendicularly intersecting the same, said boss forming a pivot center plate for supporting said underframe on a swivel truck, there being grooves of arcuate cross section formed in said wall structure along the intersection between said boss and said horizontal wall portion in the interior angle thereof, said grooves being elongated lengthwise of the car and serving to eliminate angular intersections transversely of said beam between said horizontal wall portions and said boss without interfering with the pivot function of said boss, said grooves being formed only at the sides of said cylindrical boss, the arcuate cross section of said grooves being of substantially greater radius than that of the ungrooved portions of the intersection of said horizontal wall with said cylindrical boss, each said groove contour being of maximum radius an equal distance on both sides of the transverse diameter of said cylindrical boss, the radius and depth of each said groove gradually diminishing at

both sides of said maximum radius region until each said groove disappears and the radius becomes a constant minimum value through equal distances on both sides of the longitudinal diameter of said cylindrical boss.

2. Underframe structure for a railroad car comprising a transverse beam underlyingly supported at its center and vertically loaded at its ends, said beam having spaced top and bottom walls forming respectively its tension and compression members, the central portion of said bottom wall comprising a depending vertically disposed cylindrical boss and a horizontal wall portion surrounding said boss and perpendicularly intersecting the same, said boss forming a pivot center plate for supporting said underframe on a swivel truck, there being grooves of arcuate cross section formed in said wall structure along the intersection between said boss and said horizontal wall portion in the interior angle thereof, said grooves being elongated lengthwise of the car and serving to eliminate angular intersections transversely of said beam between said horizontal wall portions and said boss without interfering with the pivot function of said boss, said grooves being formed only at the sides of said cylindrical boss, the arcuate cross section of said grooves being of substantially greater radius than that of the ungrooved portions of the intersection of said horizontal wall with said cylindrical boss, said grooves being formed wholly within said horizontal wall and each said groove contour is of maximum radius an equal distance on both sides of the transverse diameter of said cylindrical boss, the radius and depth of each said groove gradually diminishing at both sides of said maximum radius region until each said groove disappears and the radius becomes a constant minimum value through equal distances on both sides of the longitudinal diameter of said cylindrical boss.

3. Underframe structure for a railroad car comprising a transverse beam underlyingly supported at its center and vertically loaded at its ends, said beam having spaced top and bottom walls forming respectively its tension and compression members, the central portion of said bottom wall comprising a depending vertically disposed cylindrical boss and a horizontal wall portion surrounding said boss and perpendicularly intersecting the same, said boss forming a pivot center plate for supporting said underframe on a swivel truck, there being grooves of arcuate cross section formed in said wall structure along the intersection between said boss and said horizontal wall portion in the interior angle thereof, said grooves being elongated lengthwise of the car and serving to eliminate angular intersections transversely of said beam between said horizontal wall portions and said boss without interfering with the pivot function of said boss, said grooves being formed only at the sides of said cylindrical boss, the arcuate cross section of said grooves being of substantially greater radius than that of the ungrooved portions of the intersection of said horizontal wall with said cylindrical boss, said groove being formed wholly within the outer surface of said cylindrical boss and each said groove contour is of maximum radius an equal distance on both sides of the transverse diameter of said cylindrical boss, the radius and depth of each said groove gradually diminishing at both sides of said maximum radius region until each said groove disappears and the radius becomes a constant minimum value through equal distances on both sides of the longitudinal diameter of said cylindrical boss.

4. Underframe structure for a railroad car comprising a transverse beam underlyingly supported at its center and vertically loaded at its ends, said beam having spaced top and bottom walls forming respectively its tension and compression members, the central portion of said bottom wall comprising a depending vertically disposed cylindrical boss and a horizontal wall portion surrounding said boss and perpendicularly intersecting the same, said boss forming a pivot center plate for supporting said underframe on a swivel truck, there being grooves of

arcuate cross section formed in said wall structure along the intersection between said boss and said horizontal wall portion in the interior angle thereof, said grooves being elongated lengthwise of the car and serving to eliminate angular intersections transversely of said beam between said horizontal wall portions and said boss without interfering with the pivot function of said boss, said grooves being formed only at the sides of said cylindrical boss, the arcuate cross section of said grooves being of substantially greater radius than that of the ungrooved portions of the intersection of said horizontal wall with said cylindrical boss, each of said grooves being formed partly within both said horizontal wall and the exterior of said cylindrical boss and each said groove contour being of maximum radius an equal distance on both sides of the transverse diameter of said cylindrical boss, the radius and depth of each said groove gradually diminish-

5
10
15

ing at both sides of said maximum radius region until each said groove disappears and the radius becomes a constant minimum value through equal distances on both sides of the longitudinal diameter of said cylindrical boss.
